ENGINE

Carl F. Bachle, Detroit, Mich., assignor to Continental Motors Corporation, Detroit, Mich., a corporation of Virginia

Application October 8, 1931, Serial No. 567,661

19 Claims. (Cl. 123—193)

My invention relates to internal combustion engines, and more particularly to engines of the sleeve valve type.

An object of my invention is to facilitate the manufacture of engines of the aforesaid type by providing an improved cylinder construction whereby a finished product may be more readily obtained with a minimum of time and labor.

In particular, my invention is especially adapted for employment in the construction of individual cylinder structures for engines of the radial type having ports for intake and exhaust and cooperating ported sleeve valve means associated therewith.

For a more detailed understanding of my invention, reference may be had to the accompanying drawing which illustrates one embodiment of my invention, and in which:

Fig. 1 is a vertical sectional view of an engine cylinder constructed in accordance with my invention,

Fig. 2 is a sectional view through the cylinder ports taken substantially on the line 2—2 of Fig. 1,

Fig. 3 is an elevational view as viewed from the left of Fig. 2,

Fig. 4 is a fragmentary vertical sectional view of a modified construction, and

Fig. 5 is a sectional view taken on the line 5—5 of Fig. 4.

In the accompanying drawing I have illustrated an engine of the sleeve valve type and for purposes of illustration I have chosen to show my invention incorporated with a single sleeve valve engine of the Burt-McCollum type in which the sleeve valve is given a combined reciprocating and oscillating movement with respect to the sleeve and cylinder axes wherein any point on the sleeve traverses a closed path.

The present embodiment of my invention includes an engine crankcase 10 to which a cylinder structure A may be secured in any suitable manner. The cylinder structure A is provided with a central bore 11 forming a cylinder for receiving the sleeve valve means 12, a piston 13 operating within the sleeve valve and adapted for connection with an engine crankshaft (not shown) by a connecting rod 14. A cylinder head 15 is secured to the cylinder structure by bolts 16 or other suitable fastening devices and is provided with a reentrant portion 17 depending within the cylinder in spaced relation therewith to provide a sleeve pocket 18 for accommodating the outer or upper portion of the sleeve valve means. The cylinder is provided with intake and exhaust ports 19 and 20 respectively cooperating with the sleeve intake and exhaust ports 21 and 22 for controlling the cyclical events of the engine.

The outer side portion of the cylinder is preferably provided with a plurality of circumferentially extending cooling fins 23 located both above

and below the cylinder ports and that portion of the cylinder structure in the region of the ports is provided with a circumferential groove 24 having a width exceeding the height of the ports as clearly illustrated in Fig. 1. This groove preferably extends substantially around the cylinder and the said ports opening into this groove are thus exposed to the outside of the cylinder thus permitting the external machining of the ports. As shown in Fig. 2 it will be observed that I have provided a plurality of intake ports 19 and a plurality of exhaust ports 20.

In the manufacture and assembly of the engine, the cylinder fins and the groove are preferably machined, then the ports may be machined if so desired, after which the gas conducting manifold portions may be secured in place, said portions cooperating with the ports and covering or enclosing same.

Preferably, I have provided an intake manifold structure 25 and an exhaust manifold structure 26, the intake manifold structure provided with an inlet portion 27 and an arcuate fuel mixture distributing chamber 28 communicating with all of said intake ports 19, and the exhaust manifold structure is provided with an outlet portion 29 and a gas chamber 30 communicating with the exhaust ports 20. Preferably these intake and exhaust manifold structures substantially encircle the cylinder to enclose the ports (see Fig. 2) and are secured together and clamped to the cylinder by the bolts 31. These manifold structures are constructed to be secured within the groove 24 carried by the cylinder.

Furthermore, these intake and exhaust manifold structures are constructed reversible and thus either of them may be so assembled and secured to the cylinder as to direct the inlet and outlet portions respectively of the intake and exhaust manifold portions forwardly or rearwardly of the engine with respect to the slip stream as indicated by the arrow (see Fig. 2). The herein illustrated cylinder structure may be integrally cast of aluminum or other material preferably having the characteristics of aluminum, and the manifold structures, which are secured thereto and cooperate with the ports to enclose or cover same may be constructed of steel or an aluminum alloy or other suitable material.

In Figs. 4 and 5 I have illustrated a sleeve valve engine of the radial liquid cooled type in which the cylinder structure 40 is provided with jacket portions 41 and 42 respectively located above and below the ports 43, said insert such as the gas conducting structure 44 which cooperates with the ports 43 to enclose or cover same being provided with jacket portions 45 connecting the cylinder jacket portions 41 and 42.

It will be apparent to those skilled in the art to which my invention pertains that various

modifications and changes may be made therein without departing from the spirit of my invention or from the scope of the appended claims.

What I claim as my invention is:

- 5 1. In an engine of the sleeve valve type, a cylinder ported for intake and exhaust and provided with cooling fins extending substantially circumferentially around the cylinder, and gas conducting manifold portions removably secured to the cylinder to enclose same, whereby to expose said cylinder ports for machining operations from the outside prior to assembly of said manifold portions with said cylinder.
- 10 2. In an engine of the sleeve valve type, a cylinder ported for intake and exhaust and provided with cooling fins extending substantially circumferentially around the cylinder, said cylinder having a circumferential groove extending around the outside of the cylinder in the region of the cylinder ports and gas conducting manifold portions removably secured within said circumferential groove.
- 15 3. In an engine of the sleeve valve type, a cylinder ported for intake and exhaust and provided with cooling fins extending substantially circumferentially around the cylinder, said cylinder having a circumferential groove extending around the outside of the cylinder in the region of the cylinder ports, said groove extending above and below said ports, and gas conducting manifold portions removably secured within said circumferential groove.
- 20 4. In an engine of the sleeve valve type, a cylinder ported for intake and exhaust, and gas conducting manifold portions respectively cooperating with the cylinder intake and exhaust ports, said portions substantially surrounding said cylinder and removably secured thereto.
- 25 5. In an engine of the sleeve valve type, a cylinder ported for intake and exhaust, and gas conducting manifold portions respectively cooperating with the cylinder intake and exhaust ports, said portions substantially surrounding said cylinder and removably secured to each other and to the cylinder.
- 30 6. In an engine of the sleeve valve type, a cylinder and a group of intake ports and a group of exhaust ports, and gas conducting manifold portion respectively cooperating with the groups of cylinder intake and exhaust ports, said portions substantially encircling said cylinder and removably secured to the cylinder.
- 35 7. In an engine of the sleeve valve type, a cylinder ported for intake and exhaust, and reversible gas conducting manifold portions respectively cooperating with the cylinder intake and exhaust ports and removably secured to the cylinder.
- 40 8. In an engine of the sleeve valve type, a cylinder ported for intake and exhaust, and reversible gas conducting manifold portions respectively cooperating with the cylinder intake and exhaust ports, said portions substantially encircling said cylinder and removably secured thereto.
- 45 9. In an engine of the sleeve valve type, a cylinder ported for intake and exhaust and provided with a circumferential groove extending substantially around the cylinder in the region of the cylinder ports, and gas conducting manifold portions respectively cooperating with the cylinder intake and exhaust ports and removably secured within said circumferential groove.
- 50 10. In an engine of the sleeve valve type, a cylinder ported for intake and exhaust and provided with a circumferential groove extending substantially around the cylinder in the region of the cylinder ports, and reversible gas conducting manifold portions respectively cooperating with the cylinder intake and exhaust ports and removably clamped within said circumferential groove.
- 55 11. In an engine of the sleeve valve type, a cylinder ported for intake and exhaust and having cooling fins, extending circumferentially around the cylinder above and below said ports, and reversible gas conducting portions respectively cooperating with the cylinder intake and exhaust ports, said portions substantially encircling said cylinder in the region of said ports and clamped to the cylinder.
- 60 12. In an engine of the sleeve valve type, a cylinder having a plurality of circumferentially spaced intake ports exposed to the outside to permit external machining of same, and a reversible intake manifold structure cooperating with said ports to cover same.
- 65 13. In an engine of the sleeve valve type, an integrally cast cylinder having ports exposed to the outside of the cylinder, and means substantially surrounding said cylinder and cooperating with the ports for enclosing same.
- 70 14. In an engine of the water cooled sleeve valve type, a jacketed cylinder structure having ports exposed to the outside and a jacketed gas conducting structure secured about the cylinder and cooperating with said ports for enclosing same, said jacket portion of said gas conducting structure communicating with the cylinder jacket portions above and below the ports.
- 75 15. In an engine of the sleeve valve type, a cylinder having a port exposed to the outside of the cylinder, and a gas conducting manifold structure having an arcuate cylinder engaging portion secured about said cylinder to enclose said port.
- 80 16. In an engine of the type having a cylinder provided with intake and exhaust ports exposed to the outside of the cylinder, and a gas conducting manifold structure having an arcuate cylinder engaging portion secured about said cylinder to enclose said ports.
- 85 17. In an engine of the type having a cylinder provided with intake and exhaust ports exposed to the outside of the cylinder, and a gas conducting manifold structure including a plurality of complementary arcuate portions secured about said cylinder to enclose said ports.
- 90 18. In an engine of the type having a cylinder provided with intake and exhaust ports exposed to the outside of the cylinder and a gas conducting manifold structure including a plurality of complementary arcuate portions forming a structure encircling said cylinder to enclose said ports.
- 95 19. In an engine of the type having a cylinder provided with intake and exhaust ports exposed to the outside of the cylinder and a gas conducting manifold structure including complementary arcuate portions having non-communicating gas conducting passages respectively cooperating with said ports and secured about said cylinder to enclose said ports.
